UNITED STATES PATENT OFFICE.

ROBERT COALE, OF KANSAS CITY, KANSAS.

CAR-JOURNAL-BOX LID.

1,112,981.

Specification of Letters Patent.

Patented Oct. 6, 1914.

Application filed June 8, 1914. Serial No. 843,874.

To all whom it may concern:

Be it known that I, ROBERT COALE, a citizen of the United States, residing at Kansas City, in the county of Wyandotte and State of Kansas, have invented certain new and useful Improvements in Car-Journal-Box Lids, of which the following is a specification.

This invention relates to railway rolling stock and more particularly to an improved lid for the boxes for car journals, and the primary object of the invention is the provision of a hinged lid for the journal boxes, which lid is provided with an auxiliary compartment formed upon the face of the same, and having a lid hingedly connected thereto, by means of which water may be poured into the journal box for the cooling of the axle, without raising or opening the lid proper of the box. This feature provides a means for cooling the axle, without wasting the lubricating oil which is contained within the journal box, and provides for the efficient cooling of the journal in that the water poured into the box through the auxiliary door will cool the journal and upon evaporation of the same the lubricating oil will be left free within the box for lubricating the rotation of the axle.

With the foregoing and other objects in view, this invention consists in such novel features of construction, combination, and arrangement of parts as will be hereinafter more fully described, illustrated in the accompanying drawings, and claimed.

In describing the invention in detail, reference will be had to the accompanying drawings, wherein like characters designate like or corresponding parts throughout the several views, and in which:

Figure 1 is a cross sectional view showing the improved journal box lid applied to a journal box, Fig. 2 is a side elevation of the improved journal box lid, Fig. 3 is a front view, and Fig. 4 is a rear view, showing a part of the lid broken away.

Referring more particularly to the drawings, 1 designates the bottom portion of the journal box, which has the lid 2 hingedly connected thereto. The lid 2 has its upper marginal edge rolled upon itself or curved to form a hinged connection with the journal box 1. The lid 2 has an opening 5 formed therein, which opening communicates with the upper edge of the lid and extends downwardly substantially one third

of the length of the lid. The opening 5 has a box 7 encompassing the same, which box is securely attached to the outer face of the cover or lid 2, and projects outwardly therefrom, as is clearly shown in Figs. 1 and 2 of the drawings. The upper end 8 of the box 7 extends outwardly and slightly upwardly from the curved marginal edge of the cover or lid, and extends downwardly and outwardly as is shown at 9, from the point 10 thereof. A door or lid is hingedly connected to the lower marginal edge of the section 9 of the upper end of the box 7, which lid extends downwardly and abuts the outer marginal edge of the base 12 of the box. The lid 11 is hingedly connected to the box as at 14, so that access may be gained to the interior of the journal box 1, for pouring water or the like therein, for cooling the axle and the brasses, which are positioned within the journal box when it is desired to do so, without causing the waste of the lubricating oil which is in the journal box, while it provides means whereby convenient access may be gained to the journal box without lifting the entire lid 2. A spring clasp 15 is secured to the base 12 of the box 7, and engages the outer surface of the door 11, for preventing the accidental dislodgment or opening of the door.

A flat spring 16 is riveted or otherwise secured to the inner face of the lid 2, and it extends upwardly therefrom, having its upper terminal end in binding engagement with the hinge formed on the journal box 1, at the upper side of the opening therein, for holding the lid or door 2 in a closed position during the travel of the car (not shown) upon which the journal box is mounted.

In reducing the invention to practice, certain minor features of construction, combination, and arrangement of parts may necessitate alterations, to which the patentee is entitled provided such alterations are comprehended within the scope of what is claimed.

What is claimed is:

1. The combination with a journal box of the ordinary construction, of a lid hingedly connected to said journal box and provided with an opening formed near the upper marginal edge thereof, a box formed about said opening and projecting transversely of said lid upon the forward or outward side thereof, a lid hingedly connected to the upper

- end of said box, and a spring clip secured to the lower end of said box and engaging the outer surface of said lid for preventing the accidental opening thereof.
- 5 2. The combination with a journal box of the ordinary construction, of a lid hingedly connected to said journal box and provided with an opening formed near the upper marginal edge thereof, a box formed about said 10 opening and projecting transversely of said lid upon the forward or outward side thereof, a lid hingedly connected to the upper end of said box, a spring clip secured to the

lower end of said box and engaging the outer surface of said lid for preventing the 15 accidental opening thereof, a flat spring secured to the inner surface of said first named lid and extending upwardly through the central portion of said opening.

In testimony whereof I affix my signature 20 in presence of two witnesses.

ROBERT COALE.
